(57) **CLAIM**

The ornamental design for a free-standing, point-of-purchase display, as shown and described.

DESCRIPTION

FIG. 1 is a perspective view of a merchandising display embodying my invention;

FIG. 2 is a front side view thereof, the rear side view being a mirror image thereof;

FIG. 3 is a left side view thereof, the right side view being a substantial mirror image thereof; and,

FIG. 4 is a top view thereof.

The broken lines are for illustrative purposes only and form no part of the claimed design.
